UNITED STATES PATENT OFFICE.

WILLIAM J. BARR, OF CLEVELAND, OHIO.

ELECTRIC SAD-IRON.

No. 876,253.

Specification of Letters Patent.

Patented Jan. 7, 1908.

Application filed May 27, 1907. Serial No. 375,921.

To all whom it may concern:

Be it known that I, WILLIAM J. BARR, a citizen of the United States of America, residing at Cleveland, in the county of Cuyahoga and State of Ohio, have invented certain new and useful Improvements in Electric Sad-Irons; and I hereby declare the following to be a full, clear, and exact description of the invention, such as will enable others skilled in the art to which it pertains to make and use the same.

This invention relates to improvements in electrically heated sad-irons.

The primary object of this invention is to prevent overheating of the body of the sad-iron.

Another object is to automatically interrupt the electric circuit comprising the electroheating resistance in the heated sad-iron-body through the medium of a suitably supported calorically expansible member arranged and adapted to be heated and calorically expanded by and during the heating of the sad-iron-body to a predetermined extent by and during the operation of the electroheating resistance.

With these objects in view, and to the end of realizing other advantages hereinafter appearing, this invention consists in certain features of construction, and combinations of parts, hereinafter described, pointed out in the claims and illustrated in the accompanying drawings.

In the said drawings, Figure 1 is a longitudinal section of an electric sad-iron embodying my invention. Fig. 2 is a vertical section on line 2—2, Fig. 1, looking outwardly. Fig. 3 is a horizontal section on line 3—3, Fig. 1, looking downwardly. Fig. 4 is a section taken through the rear portion of the sad-iron and corresponds with Fig. 1, except that Fig. 4 illustrates the operation of the calorically expansible member arranged within the bottom of the sad-iron-body. Fig. 5 is a horizontal section on line 5—5, Fig. 1, looking downwardly.

Referring to the drawings, A indicates the body of the sad-iron. The body A is provided interiorly with a chamber A'. The chamber A' extends from a short distance above the under surface of the sad-iron-body to the top of the sad-iron-body and extends longitudinally of the sad-iron far enough to accommodate the location therein of the electroheating resistance C which rests upon the bottom of the said chamber

and is constructed or formed in any approved manner and employed in heating the sad-iron-body and consequently the bottom or ironing surface of the sad-iron-body. 60

B represents the handle of the sad-iron.

The body A is provided with a top a which is composed of asbestos or other material which is a good nonconductor of heat. The top a is secured to the body by suitably applied screws D.

The handle B is removably secured to the top a by two screws E which are shown in dotted lines Fig. 1 and spaced longitudinally of the handle and extend from within 70 the said top into the ends of the handle.

G indicates a cord which incloses and insulates the two wires H and h employed in electrically connecting opposite terminals respectively of the electroheating resistance 75 C in the sad-iron-body with opposite terminals respectively of an electric source (not shown). The wires H and h are shown electrically connected with and attached to binding-posts K and k respectively which 80

are attached to the rear end of the sad-iron-body and electrically insulated in any approved manner, as at I, from the sad-iron-body, and opposite terminals L and l of the electroheating resistance C are electrically 85

connected and suitably attached to the posts K and k respectively. The binding post k comprises a screw extending through but electrically insulated from the rear wall of 90

the chamber A' and provided externally of 95 the rear end of the sad-iron-body with a head k' which forms a stationary contact which is arranged to be straddled and electrically engaged by a movable forked contact m comprising two laterally springy members m' 95

which project and diverge toward the stationary contact k'. The movable contact m is supported in any approved manner from an insulating body 10 of porcelain or material which is a good nonconductor of electricity. The insulating body 10 constitutes 100

a member of a holder which bears the contact m, which holder comprises not only the said insulating body or contact-bearing member 10, but another insulated body 12 105

arranged between the insulating body 10 and the sad-iron-body, and both insulating bodies 10 and 12 are recessed in their opposite sides, as at 13, as required to accommodate 110

the extension of the wire h to the movable contact m with which the said wire is electrically connected, as at 14. The holder for

the movable contact m not only comprises the two insulating bodies 10 and 12 but a metal casing 15 which embraces the said insulating bodies and holds the latter together, 5 and the two insulating bodies 10 and 12 and the surrounding casing 15 are secured together by a suitably applied screw 16 which is screwed into a flat spring P which depends between the contact-holder and the rear end 10 of the sad-iron-body and is provided at its upper end with an inwardly projecting arm P' which extends forwardly over the rear portion of the sad-iron-body and is interposed between the rear end of the handle B 15 and the top a of the sad-iron-body.

It will be observed that the wire H is continually in electrical connection with the binding post K and consequently with the electroheating resistance C; that during the 20 heating of the sad-iron-body the wire h is in electrical connection with the said electroheating resistance through the medium of the movable contact m and the relatively stationary contact k' of the binding post k , 25 and that the movable contact m is electrically connected or out of electrical connection with the resistance C according as the said contact is in the one or the other of its positions. It will be observed also that the 30 holder which carries the movable contact m is arranged rearwardly of the sad-iron-body and is arranged to swing outwardly from or inwardly toward the sad-iron-body according as the movable contact is to be placed 35 out of or into electrical connection with the resistance C; that the said contact-holder at the inner extremity of its range of movement holds the contact m in electrical connection with the resistance C and at the 40 outer extremity of its said range of movement holds the said contact out of electrical connection with the said resistance; that the contact-holder-supporting spring P is under tension when the contact-holder is in its inner position holding the contact in electrical 45 connection with the resistance, and that the said spring therefore acts to hold the said contact-holder in position holding the said contact out of electrical connection with the 50 resistance.

In Fig. 1 the movable contact m is shown swung or actuated into electrical connection with the resistance C against the action of the spring P and closing the electric circuit 55 comprising the said resistance. In Fig. 4 the contact m is shown swung or actuated out of electrical connection with the resistance C.

Means instrumental in retaining the holder 60 carrying the movable contact m in position holding the said contact in electrical connection with the resistance C are provided and arranged rearward of the sad-iron-body, and the said retaining means preferably comprise a rearwardly or outwardly facing shoul-

der 17 formed on the casing 15 and a pivotally supported latch R borne by the sad-iron-body. The shoulder 17 is formed by the rear side of an upwardly projecting member 18 which is formed under the insulating body 70 10 and on the casing 15, and the latch R projects rearwardly to and over the projecting member 18 and has a projecting member 20 overlapping the aforesaid shoulder in the operative position of the latch, as shown in 75 Fig. 1.

The latch R is shown pivoted to and horizontally and transversely of the lower portion of the sad-iron-body, as at r, at the rear end and externally of the sad-iron-body. 80 The latch is provided below its axis with a downwardly projecting arm R' which in the operative position of the latch is engaged at its forward side by the rear or outer end of a calorically expansible rod or member x which 85 is composed of any suitable calorically expansible metal and is arranged longitudinally of the sad-iron-body. Preferably the rod x is arranged within a correspondingly arranged bore 22 formed within the bottom 90 of the sad-iron-body and extending from the rear extremity of the sad-iron-body forwardly a suitable distance. The inner end wall 23 of the bore 22 prevents endwise expansion of the rod toward the forward extremity of the sad-iron-body and the rod is only free therefore to expand endwise rearwardly as required to actuate the latch R into its inoperative position illustrated in 95 Fig. 4 wherein the projecting member 20 of 100 the latch is shown lifted out of engagement with the shoulder 17 of the casing of the contact-holder. It will be observed therefore that the rod x constitutes a suitably supported calorically expansible member arranged to be heated by and during the heating of the sad-iron-body by and during the operation of the resistance; that the latch R of the means instrumental in retaining the movable contact m in electrical connection 110 with the resistance is arranged to be rendered inoperative by the calorical expansion of the calorically expansible member to a predetermined extent. It will be observed also that the calorical expansible member is 115 arranged externally of the resistance where it is conveniently applied; that the said calorically expansible member is arranged within the bottom of the sad-iron-body without interfering with the exterior and ironing surface of the sad-iron-body; that the said calorically expansible member is applied within the sad-iron-body and under the resistance 120 where it is more especially convenient in connection with the location shown of the means 125 instrumental in retaining the contact in electrical connection with the resistance; that the means instrumental in retaining the movable contact m in electrical connection with the resistance is arranged externally and 130

rearwardly of the sad-iron-body where it is conveniently accessible and yet out of the way; that the insulating body 10 constitutes a member which bears the movable contact 5 *m* and is movable with the casing 15 as required to shift the contact out of or into electrical connection with the resistance; that the spring *P* although attached to the sad-iron-body is not overheated because at its 10 point of attachment to the sad-iron-body it is interposed between the handle and the top *a* which, as already indicated, is composed of material which is a good nonconductor of heat; that the spring is inexpensively attached to the contact-holder-casing 15 and acts to actuate the said casing and contents in the direction required to render the contact *m* inoperative; that the member 18 of the said casing and the latch *R* constitute 15 two coöoperating members which are interlocked in the operative position of the latch and instrumental in holding the said casing and consequently the contact *m* in the circuit-closing or operative position of the said contact. 20

25 What I claim is:—

1. The combination, with the body of a sad-iron; an electroheating resistance adapted to participate in the formation of an electric circuit and arranged to heat the said 30 body, and a suitably supported movable contact adapted to participate in the formation of the said circuit and electrically connected or out of electrical connection with the resistance according as the contact is in the one 35 or the other of its positions, of a suitably supported calorically expansible member arranged to be heated by and during the heating of the sad-iron-body by and during the operation of the resistance, and means 40 instrumental in retaining the contact in electrical connection with the resistance and arranged to be rendered inoperative by the calorical expansion of the calorically expansible member to a predetermined extent. 45

2. The combination of the body of a sad-iron; an electroheating resistance adapted to participate in the formation of an electric circuit and arranged within and instrumental in heating the said body; a suitably supported movable contact adapted to participate in the formation of the said circuit and electrically connected or out of electrical connection with the resistance according as the contact is in the one or the other of its positions; a suitably supported calorically expansible member arranged externally of the resistance and adapted to be heated by and during the heating of the sad-iron-body by and during the operation of the resistance, 55 and means instrumental in retaining the contact in electrical connection with the resistance and arranged to be rendered inoperative by the calorical expansion of the calorically expansible member to a predetermined extent. 60

3. The combination, with the body of a sad-iron; an electroheating resistance adapted to participate in the formation of an electric circuit and contained within and instrumental in heating the said body, and a suitably supported movable contact adapted to participate in the formation of the said circuit and electrically connected or out of electrical connection with the resistance according as the contact is in the one or the other 70 of its positions, of a suitably supported calorically expansible member applied within the sad-iron-body and adapted to be heated by and during the heating of the sad-iron-body by and during the operation of the 75 resistance, and means instrumental in retaining the contact in electrical connection with the resistance and arranged to be rendered inoperative by the calorical expansion of the calorically expansible member to a predetermined extent. 80

4. The combination, with the body of a sad-iron; a suitably applied electroheating resistance adapted to participate in the formation of an electric circuit and arranged to heat the said body, and a suitably supported movable contact adapted to participate in the formation of the said circuit and electrically connected or out of electrical connection with the resistance according as the 90 contact is in the one or the other of its positions, of a suitably supported calorically expansible member applied within the sad-iron-body and under the resistance and adapted to be heated by and during the heating of the sad-iron-body by and during the operation of the resistance, and means 95 instrumental in retaining the contact in electrical connection with the resistance and arranged to be rendered inoperative by the 100 calorical expansion of the calorically expansible member to a predetermined extent. 105

5. The combination, with the body of a sad-iron; an electroheating resistance adapted to participate in the formation of an electric circuit and arranged to heat the said body, and a suitably supported movable contact adapted to participate in the formation of the said circuit and electrically connected or out of electrical connection with the 110 resistance according as the contact is in the one or the other of its positions, of a suitably supported calorically expansible rod arranged to be heated by and during the heating of the aforesaid sad-iron-body by and during the 115 operation of the resistance and applied as required to accommodate the calorical expansion of the rod endwise, and means instrumental in retaining the contact in electrical connection with the resistance and arranged to be rendered inoperative by the calorical 120 expansion of the rod endwise to a predetermined extent. 125

6. The combination, with the body of a sad-iron; an electroheating resistance arranged 130

to heat the said body, and a suitably supported movable contact electrically connected or out of electrical connection with the resistance according as the contact is in the one or the other of its positions, of a suitably supported calorically expandible rod arranged longitudinally of the sad-iron-body and in position to be heated by and during the operation of the resistance, said rod being applied as required to accommodate the calorical expansion of the rod endwise, and means instrumental in retaining the contact in electrical connection with the resistance and arranged to be rendered inoperative by the calorical expansion of the rod endwise to a predetermined extent.

7. The combination, with the body of a sad-iron; an electroheating resistance adapted to participate in the formation of an electric circuit and arranged within and instrumental in heating the said body, and a suitably supported movable contact adapted to participate in the formation of the said circuit and electrically connected or out of electrical connection with the resistance according as the contact is in the one or the other of its positions; of a suitably supported calorically expandible rod applied within the body as required to accommodate the calorical expansion of the rod endwise by and during the operation of the resistance, and means instrumental in retaining the contact in electrical connection with the resistance and arranged to be rendered inoperative by the calorical expansion of the rod endwise to a predetermined extent.

8. The combination, with the body of a sad-iron; an electroheating resistance adapted to participate in the formation of an electric circuit and arranged within and instrumental in heating the said body, and a suitably supported movable contact adapted to participate in the formation of the said circuit and electrically connected or out of electrical connection with the resistance according as the contact is in the one or the other of its positions, of a suitably supported calorically expandible rod arranged under the resistance and longitudinally of the sad-iron-body, said rod being applied as required to accommodate the calorical expansion of the rod endwise by and during the operation of the resistance, and means instrumental in retaining the contact in electrical connection with the resistance and arranged to be rendered inoperative by the calorical expansion of the calorically expandible rod endwise to a predetermined extent.

9. The combination, with the body of a sad-iron; an electroheating resistance adapted to participate in the formation of an electric circuit and arranged within and instrumental in heating the said body, and a suitably supported movable contact adapted to participate in the formation of the said circuit and electrically connected or out of electrical connection with the resistance according as the contact is in the one or the other of its positions, of a suitably supported calorically expandible rod arranged longitudinally of the sad-iron-body and in position to be heated by and during the operation of the resistance, said rod being applied as required to accommodate the calorical expansion of the rod endwise, and means instrumental in retaining the contact in electrical connection with the resistance and arranged to be rendered inoperative by the calorical expansion of the rod to a predetermined extent.

cuit and electrically connected or out of electrical connection with the resistance according as the contact is in the one or the other of its positions, of a suitably supported calorically expandible rod which is arranged longitudinally of the sad-iron-body and in position to be heated by and during the operation of the resistance, said rod being only free to calorically expand endwise rearwardly relative to the sad-iron-body, and means instrumental in retaining the contact in electrical connection with the resistance and arranged to be rendered inoperative by the calorical expansion of the rod to a predetermined extent.

10. The combination, with the body of a sad-iron; an electroheating resistance adapted to participate in the formation of an electric circuit and arranged within and instrumental in heating the said body, and a suitably supported movable contact adapted to participate in the formation of the said circuit and electrically connected or out of electrical connection with the resistance according as the contact is in the one or the other of its positions, of a suitably supported calorically expandible member arranged to be heated by and during the operation of the resistance, and means arranged externally of the sad-iron-body and instrumental in retaining the contact in electrical connection with the resistance and arranged to be rendered inoperative by the calorical expansion of the calorically expandible member to a predetermined extent.

11. The combination, with the body of an electric sad-iron; an electroheating resistance adapted to participate in the formation of an electric circuit and arranged within and instrumental in heating the said body, and a suitably supported movable contact adapted to participate in the formation of the said circuit and electrically connected or out of electrical connection with the resistance according as the contact is in the one or the other of its positions, of a calorically expandible member borne by the sad-iron-body and arranged to be heated by and during the operation of the resistance, and means arranged externally of the sad-iron-body and instrumental in retaining the contact in electrical connection with the resistance and arranged to be rendered inoperative by the calorical expansion of the calorically expandible member to a predetermined extent.

12. The combination, with the body of an electric sad-iron, said body being provided with an interior chamber, and an electroheating resistance adapted to participate in the formation of an electric circuit and arranged within the said chamber and instrumental in heating the sad-iron-body, and a suitably supported movable contact adapted to participate in the formation of the said circuit and electrically connected or out of electrical connection with the resistance according as the contact is in the one or the other of its positions, of a calorically expandible member borne by the sad-iron-body and arranged to be heated by and during the operation of the resistance, and means arranged externally of the sad-iron-body and instrumental in retaining the contact in electrical connection with the resistance and arranged to be rendered inoperative by the calorical expansion of the calorically expandible member to a predetermined extent.

electrical connection with the resistance according as the contact is in the one or the other of its positions, of a calorically expandible rod arranged within the bottom of the 5 said chamber and longitudinally of the sad-iron-body, said rod extending to the rear end of the sad-iron-body and being only free to calorically expand endwise and rearwardly relative to the sad-iron-body by and 10 during the operation of the resistance, and means instrumental in retaining the contact in electrical connection with the resistance and arranged to be rendered inoperative by the calorical expansion of the rod endwise to 15 a predetermined extent.

13. The combination, with the body of an electric sad-iron, and an electric resistance adapted to participate in the formation of an electric circuit and arranged within and instrumental in heating the said body, and a 20 suitably supported movable contact arranged externally of the sad-iron-body and adapted to participate in the formation of the said circuit and electrically connected or 25 out of electrical connection with the resistance according as the contact is in the one or the other of its positions, of a calorically expandible member supported from the sad-iron-body and arranged to be calorically ex- 30 panded by and during the operation of the resistance, and means instrumental in retaining the contact in electrical connection with the resistance and arranged to be rendered inoperative by the calorical expansion 35 of the calorically expandible member to a predetermined extent.

14. The combination, with the body of an electric sad-iron, and an electroheating resistance adapted to participate in the formation of an electric circuit and instrumental in heating the said body, and a movable contact adapted to participate in the formation of the said circuit and electrically connected or out of electrical connection with the resistance; 40 according as the contact is in the one or the other of its positions, of a suitably supported member bearing the contact and movable as required to shift the contact out of or into electrical connection with the resistance; 45 a calorically expandible member borne by the sad-iron-body and arranged to be heated during the operation of the electroheating resistance, and means which is not only instrumental in holding the contact-bearing mem- 50 ber in the position required to electrically connect the contact with the resistance but arranged to be rendered inoperative by the calorical expansion of the calorically expandible member to a predetermined extent.

60 15. The combination, with the body of an electric sad-iron, and an electroheating resistance adapted to participate in the formation of an electric circuit and instrumental in heating the said body, and a movable contact adapted to participate in the formation

of the said circuit and electrically connected or out of electrical connection with the resistance according as the contact is in the one or the other of its positions, of a suitably supported member bearing the contact and mov- 70 able as required to shift the contact out of or into electrical connection with the resistance; a suitably supported calorically expandible member arranged to be calorically expanded by and during the operation of the resistance; 75 means which is not only instrumental in holding the contact-bearing member in the position required to electrically connect the contact with the resistance but arranged to be rendered inoperative by the calorical ex- 80 pansion of the calorically expandible member to a predetermined extent, and means acting to retain the contact-bearing member in position holding the contact out of electrical connection with the resistance. 85

16. The combination, with the body of an electric sad-iron, and an electroheating resistance adapted to participate in the formation of an electric circuit and instrumental in heating the said body, and a movable contact adapted to participate in the formation of the said circuit and electrically connected or out of electrical connection with the resistance according as the contact is in the one or the other of its positions, of a suitably 90 supported member bearing the contact and movable as required to shift the contact out of or into electrical connection with the resistance; a calorically expandible member borne by the sad-iron-body and arranged to 100 be calorically expanded by and during the operation of the resistance; means which is not only instrumental in holding the contact-bearing member in the position required to electrically connect the contact with the resistance but arranged to be rendered inoperative by the calorical expansion of the calorically expandible member to a predetermined extent, and a suitably applied spring 105 acting to retain the contact-bearing member 110 in position holding the contact out of electrical connection with the resistance.

17. The combination, with the body of an electric sad-iron, an electroheating resistance adapted to participate in the formation of an 115 electric circuit and instrumental in heating the said body, and a movable contact adapted to participate in the formation of the said circuit and electrically connected or out of electrical connection with the resistance ac- 120 cording as the contact is in the one or the other of its positions, of a suitably supported member bearing the contact and movable as required to shift the contact out of or into electrical connection with the resistance; a 125 suitably supported calorically expandible member arranged to be calorically expanded by and during the operation of the resistance; means which is not only instrumental in holding the contact-bearing member in the 130

- position required to electrically connect the contact with the resistance but arranged to be rendered inoperative by the calorical expansion of the calorically expansible member 5 to a predetermined extent, and a spring attached to the sad-iron-body and acting to retain the contact-bearing member in position holding the contact out of electrical connection with the resistance.
- 10 18. The combination, with the body of an electric sad-iron; an electroheating resistance arranged within the said body and adapted to participate in the formation of an electric circuit, and a movable contact adapted to 15 participate in the formation of the said circuit and in its operative position being electrically connected with a terminal of the resistance and thereby closing the circuit, of a suitably supported member bearing the said 20 contact and movable as required to actuate the contact out of or into electrical connection with the resistance; a calorically expansible member borne by the sad-iron-body and arranged to be heated by and during the 25 operation of the resistance; means instrumental in locking or holding the contact-bearing member in the circuit-closing position of the contact and arranged to be rendered inoperative by the calorical expansion 30 of the calorically expansible member to a predetermined extent, and means acting to actuate the contact-bearing member in the direction required to render the contact inoperative.
- 35 19. The combination, with the body of an electric sad-iron; an electroheating resistance arranged within the said body and adapted to participate in the formation of an electric circuit, and a movable contact arranged 40 externally of the sad-iron-body and adapted to participate in the formation of the said circuit and in its operative position electrically connected with the terminal of the resistance and thereby closing the circuit, of a member 45 arranged externally of and supported from the sad-iron-body and bearing the said contact and movable as required to actuate the contact out of or into electrical connection with the resistance; a calorically expansible 50 member arranged within the sad-iron-body and in position to be heated during the operation of the resistance; means instrumental in holding the contact-bearing member in the circuit-closing position of the contact 55 and arranged to be rendered inoperative by the calorical expansion of the calorically expansible member to a predetermined extent, and means acting to actuate the contact-bearing member in the direction required to 60 render the contact inoperative.
20. The combination, with the body of an electric sad-iron; an electroheating resistance arranged to heat the said body and adapted to participate in the formation of an electric circuit, and a movable contact adapted to 65
- participate in the formation of the said circuit and electrically connected or out of electrical connection with the resistance according as the contact is in the one or the other of its positions, of a suitably applied spring 70 bearing the contact and acting to hold the contact out of electrical connection with the resistance; a suitably applied calorically expansible member arranged to be heated by and during the operation of the resistance, 75 and means instrumental in retaining the contact in electrical connection with the resistance and arranged to be rendered inoperative by the calorical expansion of the calorically expansible member to a predetermined 80 extent.
21. The combination, with the body of an electric sad-iron; an electroheating resistance arranged within and instrumental in heating the said body and adapted to participate in 85 the formation of an electric circuit, and a movable contact arranged externally of the sad-iron-body and adapted to participate in the formation of the said circuit and electrically connected or out of electrical connection 90 with the resistance according as the contact is in the one or the other of its positions, of a spring attached to the sad-iron-body and bearing the contact and acting to hold the contact out of electrical connection with the 95 resistance; a suitably applied calorically expansible member arranged to be heated by and during the operation of the resistance, and means instrumental in retaining the contact in electrical connection with the resistance and arranged to be rendered inoperative by the calorical expansion of the calorically expansible member to a predetermined 100 extent.
22. The combination, with the body of an 105 electric sad-iron, said body having a top composed of material which is a good non-conductor of heat; an electroheating resistance arranged within the said body and adapted to participate in the formation of an electric 110 circuit, and a movable contact arranged externally of the sad-iron-body and adapted to participate in the formation of the said circuit and electrically connected or out of 115 electrical connection with the resistance according as the contact is in the one or the other of its positions, of a spring attached to the aforesaid top and bearing the contact and acting to hold the contact out of electrical connection with the resistance; a suitably applied calorically expansible member 120 arranged to be heated by and during the operation of the resistance, and means instrumental in retaining the contact in electrical connection with the resistance and 125 arranged to be rendered inoperative by the calorical expansion of the calorically expansible member to a predetermined extent.
23. The combination, of the body of an electric sad-iron; an electroheating resist- 130

5 aance arranged to heat the said body and adapted to participate in the formation of an electric circuit, and a suitably supported movable contact arranged externally of and movable from and toward the sad-iron-body and adapted to participate in the formation of the said circuit and electrically connected or out of electrical connection with the resistance according as the contact is in its inner or outer position; means acting to retain 10 the contact in its outer position; a suitably applied calorically expansible member arranged to be heated by and during the operation of the resistance, and means instrumental in retaining the contact in its inner position and arranged to be rendered inoperative by the calorical expansion of the calorically expansible member to a predetermined extent.

15 20 24. The combination of the body of an electric sad-iron; an electroheating resistance arranged to heat the said body and adapted to participate in the formation of an electric circuit, and a suitably supported movable contact arranged rearward and movable from and toward the rear end of the sad-iron-body and adapted to participate in the formation of the said circuit and electrically connected or out of electrical connection 25 with the resistance according as the contact is at the one or the other extremity of its range of movement; means acting to retain the contact out of electrical connection with the resistance; a suitably applied calorically 30 expansible member arranged to be heated by and during the operation of the resistance, and means instrumental in retaining the contact in electrical connection with the resistance and arranged to be rendered inoperative 35 by the calorical expansion of the calorically expansible member to a predetermined extent.

35 40 45 50 55 60 65 25. The combination of the body of an electric sad-iron; an electroheating resistance arranged to heat the said body and adapted to participate in the formation of an electric circuit, and a movable contact arranged externally of the sad-iron-body and supported as required to render it capable of being swung toward or from the sad-iron-body, said contact being adapted to participate in the formation of the said circuit and electrically connected or out of electrical connection with the resistance according as the contact is at the inner or outer extremity of its range of movement; a calorically expansible member arranged to be heated by and during the operation of the resistance, and means instrumental in retaining the contact in electrical connection with the resistance, said retaining means being arranged to be rendered inoperative by the calorical expansion of the calorically expansible member to a predetermined extent and thereby rendering the contact free to be swung outwardly.

26. The combination, with the body of an electric sad-iron; an electroheating resistance arranged to heat the said body and adapted to participate in the formation of an electric circuit; a contact adapted to participate in the formation of the said circuit, and a suitably supported movable contact-holder comprising a body of insulating material which bears the contact and is embraced and borne by a casing, said contact-holder holding the contact in or out of electrical connection with the resistance according as the contact-holder is at the one or the other extremity of its range of movement, of a suitably applied calorically expansible member arranged 70 to be heated by and during the operation of the resistance, and means instrumental in retaining the contact-holder in position holding the contact in electrical connection with the resistance, said retaining means comprising two coöperating members which are interlocked in the last-mentioned position of the contact-holder, said coöperating members being supported the one independently of and movable relative to the other which is 75 formed on the aforesaid casing and the former being arranged to be actuated and thereby rendered inoperative by the calorical expansion of the calorically expansible member to a predetermined extent. 80

27. The combination, with the body of an electric sad-iron; an electroheating resistance arranged to heat the said body and adapted to participate in the formation of an electric circuit; a contact adapted to participate in the formation of the said circuit, and a suitably supported movable contact-holder comprising a body of insulating material which bears the contact and is embraced and borne by a casing, said contact-holder holding the contact in or out of electrical connection with the resistance according as the contact-holder is at the one or the other extremity of its range of movement, of a suitably applied calorically expansible member arranged 90 to be heated by and during the operation of the resistance, and means instrumental in retaining the contact-holder in position holding the contact in electrical connection with the resistance, said retaining means comprising an outwardly facing shoulder formed on the aforesaid casing and a suitably supported pivotal latch borne by the sad-iron-body and having a projecting member overlapping the aforesaid shoulder 95 100 105 110 115 120 125 in the operative position of the latch, said latch being arranged to be actuated into its inoperative position by the calorical expansion of the calorically expansible member to a predetermined extent.

28. The combination, with the body of an electric sad-iron; an electroheating resistance arranged to heat the said body and adapted to participate in the formation of an electric circuit, and a contact arranged 130

externally and rearwardly of the sad-iron-body and adapted to participate in the formation of the said circuit, of a suitably supported contact-holder arranged rearward of and movable outwardly from and inwardly toward the sad-iron-body, said contact-holder holding the contact in or out of electrical connection with the resistance according as the contact-holder is in its inner 10 or outer position; a suitably applied calorically expandible member arranged to be heated by and during the operation of the resistance, and means instrumental in retaining the contact-holder in its inner position and comprising two coöperating members which are interlocked in the inner position of the contact-holder, said coöperating members being supported the one by the sad-iron-body and independently of and 20 movable relative to the other which is borne by the contact-holder, and the former being arranged to be actuated and thereby rendered inoperative by the calorical expansion of the calorically expandible member to a 25 predetermined extent.

29. The combination, with the body of an electric sad-iron; an electroheating resistance arranged to heat the said body and adapted to participate in the formation of 30 an electric circuit, and a contact adapted to participate in the formation of the said circuit, of a movable contact-holder comprising a body of insulating material which bears the contact and is embraced and borne by a 35 casing, said contact-holder holding the contact in or out of electrical connection with the resistance according as the contact-holder is at the one or the other extremity of its range of movement, of a suitably supported spring bearing the aforesaid casing and acting to hold the contact-holder in position holding the contact out of electrical connection with the resistance; a suitably 40

applied calorically expandible member arranged to be heated by and during the operation of the resistance, and means instrumental in retaining the contact-holder in position holding the contact in electrical connection with the resistance, said retaining means being arranged to be rendered in- 45 operative by the calorical expansion of the calorically expandible member to a pre- 50 determined extent.

30. The combination, with the body of an electric sad-iron; an electroheating resist- 55 ance arranged to heat the said body and adapted to participate in the formation of an electric circuit, and a contact arranged externally and rearwardly of the sad-iron-body and adapted to participate in the formation 60 of the said circuit, of a contact-holder movable outwardly from or inwardly toward the sad-iron-body and comprising a body of insulating material which bears the contact and is embraced and borne by a casing, said 65 contact-holder holding the contact in or out of electrical connection with the resistance according as the contact-holder is in its inner or outer position; a suitably supported spring bearing the said casing and acting to 70 hold the contact-holder in its outer position; a suitably applied calorically expandible member arranged to be heated by and during the operation of the resistance, and means instrumental in retaining the contact- 75 holder in its inner position and arranged to be rendered inoperative by the calorical expansion of the calorically expandible member to a predetermined extent.

In testimony whereof, I sign the foregoing 80 specification, in the presence of two witnesses.

WILLIAM J. BARR.
